UNITED STATES PATENT OFFICE.

ARTHUR R. RULE, OF WESTFIELD, NEW JERSEY.

DESIGN FOR A DISPLAY-CARD.

51,737.

Specification for Design.

Patented Feb. 5, 1918.

Application filed November 16, 1917. Serial No. 202,416. Term of patent 7 years.

To all whom it may concern:

Be it known that I, ARTHUR R. RULE, a citizen of the United States, residing in Westfield, county of Union, and State of New Jersey, have invented a new, original, and ornamental Design for Display-Cards, of which the following is a specification, reference being had to the accompanying drawings, forming a part thereof.

In the drawings,—

Fig. 2 is a side view thereof.

I claim:

The ornamental design for a display card, substantially as shown.

This specification signed and witnessed this 24 day of October, 1917.

ARTHUR R. RULE.

Witnesses:

A. E. WEIMUTH,

A. C. OTT.
